H. R. VAN DEVENTER,
COMBINED GENERATOR AND PUMP.
APPLICATION FILED MAY 25, 1916.

1,349,397.

Patented Aug. 10, 1920.

INVENTOR

H. R. Van Deventer

UNITED STATES PATENT OFFICE.

HARRY RANDOLPH VAN DEVENTER, OF SUMTER, SOUTH CAROLINA, ASSIGNOR TO
SPLITDORF ELECTRICAL COMPANY, OF NEWARK, NEW JERSEY, A CORPORA-
TION OF NEW JERSEY.

COMBINED GENERATOR AND PUMP.

1,349,397.

Specification of Letters Patent. Patented Aug. 10, 1920.

Application filed May 25, 1916. Serial No. 99,855.

To all whom it may concern:

Be it known that I, HARRY RANDOLPH VAN DEVENTER, a citizen of the United States, residing at Sumter, in the county of Sumter 5 and State of South Carolina, have invented certain new and useful Improvements in Combined Generators and Pumps, of which the following is a specification, reference being had to the accompanying drawing.

10 My invention relates to a combined dynamo and pump for supplying ignition current and pumping lubricant to an engine.

DYNAMOS commonly known as magnetos are used on motors for vehicles, and on stationary and marine engines. Such motors often require a pump for circulating the cooling water or the lubricant, and it has heretofore been customary to furnish the magneto as one unit and the pump as another, each one of these accessories having its 20 separate base, driving shaft, and other parts.

The object of my invention is to combine the magneto and pump in a single unit 25 structure, ready to mount on the engine. A further object is to provide a magneto that may be used as an oil pump and not require any lubrication, other than that furnished by the oil circulated.

30 Another object is to provide a magneto in which the revolving element will act as the impeller of the pump, said revolving element being entirely inclosed by the field structure and other parts of the magneto.

35 A further object is to provide an improved system of ignition and lubrication for engines.

There are other objects as hereinafter pointed out and included within the scope 40 of the appended claims.

In the accompanying drawing in which like figures of reference denote the same parts wherever they are shown,

Figure 1 is a side view of a rotor used in 45 the combined dynamo and pump embodying one form of my invention;

Fig. 2 is a sectional view of my combined dynamo and pump on the line B—B of Fig. 3 of the drawing, the generating coil not 50 being sectioned;

Fig. 3 is a sectional view on the line A—A of Fig. 2, the generating coil being shown in end view.

My improved dynamo and pump consists of a supporting base 1 which has upwardly 55 extending portions 2—2. Secured to these upwardly extending portions are pole pieces 14 and 15. Said pole pieces and the upwardly extending parts of the base are provided with a cylindrical recess within which 60 fits and rotates a rotor 6. Said rotor 6 is mounted on a shaft 9 which is mounted in suitable bearings. At opposite ends of the rotor there are end plates 3 and 4 respectively. A cover plate 5 closes an opening in 65 the upwardly projecting parts 2 of the base structure. The pole pieces extend upwardly and are mounted between the upper ends thereof is a generating coil 13. Mounted on the base 1 are magnets M. These magnets embrace 70 the end plates 3 and 4 and furnish flux to the rotor, the rotor operating in the well known way to reverse the flux through the generating coil 13. Said rotor as is well understood in this art, is provided with pole 75 shoes which are spaced from each other and non-magnetic material fills the space between the shoes, forming with the pole shoes a cylindrical body portion. The body portion of the rotor is provided with chambers 80 7 and 8 the walls of which are curved, as clearly indicated in Fig. 2. These chambers extend only partway throughout the length of the rotor, as indicated in dotted lines in Fig. 3. The pole piece 14 is cut away to 85 form a chamber 11^a which opens into the cylindrical chamber in which the rotor operates. A pipe 11 extends through the projecting portion 2 of the base and is adapted to discharge into the chamber 11^a. A 90 chamber 10^a is formed in the pole shoe on the opposite side of the rotor and this chamber opens into the chamber in which the rotor operates. A pipe 10 is connected to the chamber 10^a and is adapted to receive the 95 oil discharged by the rotor into the chamber 10^a.

The operation of my device as a dynamo, will be obvious from the above description. As the rotor rotates with the shaft 9, the 100 flux of the magnets M—M will be caused to flow intermittently and in reverse directions through the coil 13, thus generating a current in a primary winding in said coil and this primary winding may be controlled 105 by a suitable interrupter mechanism mount-

ed in the casing 12. The interrupting of the primary circuit produces a current in the secondary of the generating coil.

- The rotor turns in the direction indicated 5 by the arrow in Fig. 2. A certain part of the oil discharged in the chamber 11^a will be taken up by the chambers 7 and 8 in succession and will be forced out of these chambers by centrifugal force into the chamber 10^a and thence into the pipe 10 causing the circulation of the oil out through the pipe 10, to the parts to be lubricated and back again through the pipe 11 into the chamber 11^a. It will be noted that the generating coil 15 is remote from the rotor and that the rotor is substantially housed by the supporting base, the pole pieces and the cover plate 5, so that there is no chance for the oil to come in contact with the generating coil.
- 20 It will be obvious that minor changes in the details of construction and arrangement of parts, may be made without departing from the spirit of the invention, as set forth in the appended claims.
- 25 Having thus described my invention, I claim:
1. A combined dynamo and pump including in combination, a supporting structure, a stationary coil, a rotor for directing flux 30 through said stationary coil, said rotor being inclosed and separated from said coil, inlet and outlet pipes connected to said supporting structure, said rotor being constructed so as to operate as an impeller for 35 taking the oil from the inlet pipe and forcing the same out through the outlet pipe.

2. A combined dynamo and pump including in combination a supporting structure, pole pieces carried thereby, a generating winding mounted on the pole pieces, a rotor 40 for directing a flux through said generating coil, said supporting structure having a cylindrical chamber in which said rotor fits and rotates, independent chambers opening into the rotor chamber, a pipe leading to 45 each chamber, said rotor being constructed so as to serve as an impeller for taking oil from one of said chambers and forcing the same out into the other chamber.

3. A combined dynamo and pump including in combination a supporting structure, pole pieces in said supporting structure, said supporting structure and pole pieces having a cylindrical chamber formed therein, a rotor disposed within said cylindrical chamber, a generating coil carried by the pole pieces, said rotor being completely housed in the supporting structure and separated from said generating coil, independent chambers 55 opening into the cylindrical chamber for the 60 rotor, a pipe connected with each chamber in the supporting structure, said rotor having chambers formed therein, the walls of which are curved so that oil taken from one of the chambers in the supporting structure 65 by the rotor will be forced outwardly into the other chamber in said supporting structure.

In testimony whereof I hereunto affix my signature.

HARRY RANDOLPH VAN DEVENTER.
